Letters Patent.

The schedule referred to in the Letters Patent, and making part of the same, containing a description in the words of the said Act, thereof, himself of his improvement in the musical instrument called the Guitar.

To all whom these presents may concern. —

Be it known that I, Est. Sher of the city of Philadelphia have invented a new and useful improvement in the musical instrument called the guitar. The instrument improved by me is called the Harp guitar; all guitars heretofore used, have been used ^{either} whilst held in the hands of the player, or on his or her lap; the harp guitar is in length, four feet ten inches longer than the common guitar by about one foot & a half; it is not played when held in the hands or on the lap, of the performer, but rests on the floor and is played just as a harp is. The shape of the harp guitar may be varied to suit the taste of the owner or the player; that shape used by your petitioner, is as described in a sketch already transmitted to the patent office, and will more at large appear by a lithographic representation now preparing in the wood, strings &c except as to the size and extent thereof. The Harp guitar and the common guitar are similar. The improvement for which a patent is asked, is in the enlargement & adaptation of the instrument, whatever may be its shape, so that it may be played resting on the floor, combining the characteristics of the guitar and harp; so that in reality, the improvement is, that the Harp guitar is played resting on the floor.

The advantages of this improvement are great
and readily perceived by any one acquainted
with either Map or Chart.
